UNITED STATES PATENT OFFICE.

CHESTER T. MINKLER, OF NEWPORT, RHODE ISLAND, ASSIGNOR TO THE GOVERNMENT OF THE UNITED STATES.

DRIFTING MINE.

1,295,051.

Specification of Letters Patent.

Patented Feb. 18, 1919.

Application filed September 29, 1917. Serial No. 194,075.

To all whom it may concern:

Be it known that I, CHESTER T. MINKLER, a citizen of the United States, residing at Newport, in the county of Newport and 5 State of Rhode Island, have invented certain new and useful Improvements in Drifting Mines, of which the following is a specification.

This invention relates to submarine mines, 10 and in its more intense aspect to mines of the drifting type, adapted to be suspended from floats on the surface of the water and exploded by contact, although by changing the buoyancy they may be used for set mines 15 if desired.

As is well known, drifting mines of this 20 general character form a valuable weapon in special instances of battle tactics as when launched from fast destroyers for the purpose of causing the enemy battle line to turn and subject itself to tactical disadvantage or cause actual injury to his forces if he continues into the mine field.

One of the objects of the present invention 25 is to provide a mine of the above general character, which will be safe to handle under ordinary conditions, yet be reliable and highly efficient when in use. A further object is to provide a mine of the above general character, having relatively few parts which may be simply and inexpensively constructed. A further object is to provide a mine of the above character which may be 30 easily and quickly set and which will float 35 or drift indefinitely in armed condition, or sink after a predetermined time.

Other objects will be in part obvious from the annexed drawings and in part indicated in connection therewith by the following 40 analysis of this invention.

This invention accordingly consists in the features of construction, combination of parts and in the unique relations of the members and in the relative proportioning 45 and disposition thereof; all as more completely outlined herein.

To enable others skilled in the art so fully to comprehend the underlying features of the invention that they may embody the 50 same into numerous modifications in structure and relation contemplated by this invention and embraced within the scope of the appended claims, drawings depicting a preferred form have been annexed as a part 55 of this disclosure, and in such drawings,

like characters of reference denote corresponding parts throughout all the views, of which:

Figure 1 is a vertical sectional view of such parts of a complete mine, in safety position, as are necessary to fully understand the present invention.

Fig. 2 is a fragmentary view showing the firing mechanism in firing position.

Figs. 3 and 4 are detail sectional views of the sinking valve.

Referring now to the drawings in detail, and more particularly to Figs. 1 and 2, 1 denotes the upper part of the outer shell of a mine of the drifting type adapted to form 70 an air chamber preferably of such capacity that the entire mine when placed overboard is of but slight negative buoyancy, and 2 denotes the lower part of the shell containing the explosive charge. These two sections are welded together and separated by a diaphragm 3.

The lower part of the explosive chamber is provided with a base supporting the firing mechanism hereinafter described and 80 contained within a chamber 5 concavely formed in the lower part of the mine casing.

The upper part of the mine is provided with a handling ring 6 threaded into a concave spider 7, whereby when not in use it 85 may occupy a position, as shown, below the upper surface of the mine, thus permitting the mines to be conveniently stacked and stored. This ring besides being useful in handling and launching the mine is also 90 adapted to be connected by means of a bridle (not shown) with one or more other mines spaced apart therefrom.

The upper part of the firing mechanism chamber 5 is provided with a ring 8 into 95 which is threaded a nipple 10 carrying a primer charge 11, centrally disposed within which is a detonator 12 carried by the upper end of a tubular member 13, the lower end of which is connected to and supported by a 100 shield 14 bolted to a base plate 15, which in turn is carried by the ring 4. Between the base plate 15 and shield 14 is positioned a flexible diaphragm 16, engaging the under side or bottom of a longitudinal movable 105 member 17. Threaded within this member 17 is a sleeve 18 carrying at its upper end a bushing 20 surrounding a firing pin stud 21, and carrying at its end a firing pin proper 22 adapted to engage the detonator 12. 110

Within the sleeve 18 is a coiled firing spring 23 engaging the end of the firing pin stud 21, and coiled about the outer surface of the sleeve 18 is a hydrostatic piston spring 24 adapted to be compressed as the diaphragm 16 moves upwardly into the position shown in Fig. 2, for the purpose of preventing too rapid movement thereof as the mine is submerged, but more especially to hold the diaphragm down during shipment and to prevent shock if the mine should be dropped.

In the base plate 15 is an opening or cavity provided with a check valve such as ball 25 normally closed by means of a cap 26. A tube 27 leads from the chamber holding the ball 25 to the central part of the hydrostatic chamber 28 whereby on removal of the cap 26 water will enter through this pipe 27 on submergence of the mine and force the diaphragm 16 upwardly into the position shown in Fig. 2. This movement compresses the springs 23 and 24 whereby the firing pin 21 will be driven into contact with the detonator when released.

A stud 30 projects outwardly through a slot 31 in the side of the tube 13, and is carried by the sleeve 18 when moved by upward movement of the diaphragm 16. This stud 30 supports a cam plate 32 adapted to be engaged by an adjusting screw 33, carried by an arm 34 of a three arm trigger member 35 supported upon a bracket 36 projecting from the tube 13. In the position shown in Fig. 1, the arm 34 of the trigger member is prevented from moving toward the left by reason of the adjusting screw 33 engaging this cam plate 32, but when the cam plate has been raised, as shown in Fig. 2, then the trigger is free to move about its pivotal support 37, as will hereinafter appear. This bracket 36 also carries a lever 38 pivoted at 40 intermediate its ends, one end of which is adapted to be engaged by the upper arm 41 of the trigger 35, while the opposite end 42 extends inwardly through the slot 31 in the tube 13 to engage the firing pin stud 21. A third arm 43 of the trigger 35 supports the upper end of a turnbuckle link 44, the lower end of which is pivotally connected with a tripping weight 45 or other suitable momentum actuated device. A second link 46 connects the lower part of the tripping weight 45 with the lower end of a yoke 39 extending downwardly from the bracket 36.

From the above it will be seen that after removing the ball check-valve cap 26 water will enter the hydrostatic chamber and force the diaphragm 16 upwardly to compress the springs 23 and 24, thus releasing the safety device 32 associated with the trigger 35. Thereafter should a boat contact with the mine, the delicately balanced tripping weight 45 will tend to oscillate and such oscillations will release the upper end of the

trigger arm 41 from engagement with the lever 38, permitting the spring 23 to force the firing pin stud 21 strongly upwardly into impact upon the detonator 12, as shown in Fig. 2.

70

In the base plate 15, there is provided an opening at any convenient point adapted to receive a sinking valve, shown in Figs. 3 and 4. This valve is for the purpose of causing the mine to sink after it has remained in the water a predetermined time. If it is desired that the mine remain afloat indefinitely, the opening is kept closed by any suitable plug, but when the sinking of the mine is desired, the sinking valve is inserted after removing this plug.

This sinking valve comprises a tubular member 50 adapted to be inserted or screwed into the opening, and is provided with holes 51 and a valve 52 normally closing the holes 51 and held in closed position by means of a bushing 53 of sal ammoniac, or other suitable material adapted to dissolve on contact with the water. After this bushing is dissolved, the valve is raised by means of a spring 54 and pressure of the water to position shown in Fig. 4, thereby allowing the water to enter through holes 51 to the interior of the firing chamber 5, thereby increasing the slight negative buoyancy of the mine provided for by regulating the size of the air chamber at the top of the mine and counterbalanced by the float and causing the mine to sink.

It is believed the method of use and operation of the device herein set forth will be clear to those familiar with the art from the above description. It may be stated, however, that the mines are stored in substantially the condition shown in Fig. 1, after having been filled with TNT through an opening closed by plug 48, and when it is desired to place the same in operation a suitable float is attached to the handling ring 6, the cap 26 removed, and the mine launched, either singly or in pairs connected by a bridle, as previously set forth. As soon as the mine is launched, it sinks to the depth permitted by the float line, and the water enters through the check-valve 25 flooding the hydrostatic chamber 28 and forcing the diaphragm 16 upwardly to the position shown in Fig. 2. This upward movement of the diaphragm carries with it the safety plate 32 thereby leaving the trigger 35 free to be released on oscillation of the tripping weight 45 caused by contact of a boat with the mine. When the trigger is tripped, the spring 23, which is under compression due to the expansion of the hydrostatic chamber 28, will force the firing pin 22 upwardly to explode the detonator 12 and fire the charge contained within the casing adjacent thereto.

If it is desired that the mine should sink after a predetermined time, such as a period

100

105

110

115

120

125

130

of one hour, as would be the case where a pursued vessel was sowing mines in the path of a pursuing fleet, at which time the pursuer would have passed; then the plug in the 5 base plate 15 is removed and the sinking valve, shown in Figs. 3 and 4, inserted therein, which operates as above described.

It is thus seen that the present invention provides a simple and practical mine of the 10 drifting type, which will be reliable and efficient in use and operation, and adapted to accomplish, among others, all the objects and advantages herein set forth. It will also be apparent that by increasing the 15 size of the buoyancy chamber the mine may be given positive buoyancy effect so that it will not sink of itself and thus may be anchored indefinitely in a fixed place.

Without further analysis, the foregoing 20 will so fully reveal the gist of this invention that others can by applying current knowledge readily adapt it for the various applications without omitting certain features that, from the standpoint of the prior 25 art, fairly constitute essential characteristics of the generic or specific aspects of this invention, and therefore such adaptations should and are intended to be comprehended within the meaning and range of equivalency of the following claims.

I claim as my invention:

1. In a submarine mine, in combination, a 30 casing having an air chamber near one end and an explosive chamber near the other, one end of said chamber being concave and provided with firing means, said firing means including a hydrostatically tensioned firing pin, a multi-arm trigger mechanism therefor, a momentum actuated means connected 35 with one arm of said trigger mechanism and adapted to release said mechanism, and a safety device associated with another arm for said trigger mechanism adapted to prevent actuation thereof until said hydrostatically actuated firing pin has been placed under tension.

2. In a submarine mine, in combination, a 40 casing having an explosive chamber, said explosive chamber having a cavity adapted to house a firing mechanism, means closing the cavity adapted to support the firing mechanism and forming therewith an expansible hydrostatic chamber, a firing pin, a spring adapted to be compressed on expansion of said hydrostatic chamber, a safety device releasable on compression of said spring, a pivoted trigger for said firing pin directly associated with said safety device, and means adapted to release said 45 trigger when the mine is engaged, said means comprising a weight flexibly connected at one end to said closing means and at its other end to said trigger.

3. In a submarine mine, in combination, a 50 casing having an explosive chamber, said ex-

plosive chamber having a cavity adapted to house a firing mechanism, means closing the cavity adapted to support the firing mechanism and forming therewith an expansible hydrostatic chamber, a firing pin, a spring 55 adapted to be compressed on expansion of said hydrostatic chamber, a pivoted trigger for said firing pin, and means adapted to move said trigger about its axis to release said firing pin when the mine is engaged, 60 said means comprising a weight flexibly supported at either end, and means whereby the cavity in the explosive chamber may be filled after a predetermined time to cause the mine to sink.

4. In a submarine mine, in combination, a casing having an air chamber, and an explosive chamber, said explosive chamber having a cavity adapted to house a firing mechanism, a means closing the cavity 65 adapted to support the firing mechanism and forming therewith an expansible hydrostatic chamber, a firing pin, a spring adapted to be compressed on expansion of said hydrostatic chamber, a safety device including a cam member and a cooperating arm releasable on compression of said spring, a pivoted trigger for said firing pin directly connected with said safety device, and means adapted to release said trigger when 70 the mine is engaged, said means comprising a weight flexibly supported at either end, and means whereby one of said chambers may be filled after a predetermined time to cause the mine to sink, said means including a valve and a protector for said 75 valve adapted to dissolve and permit the valve to open.

5. In a submarine mine, in combination, a casing having an air chamber, an explosive- 80 containing chamber, and a firing mechanism chamber associated with the explosive chamber and containing the firing mechanism, said firing mechanism comprising a detonator, a firing pin, a spring adapted to 85 be compressed by hydrostatic pressure to tension said firing pin, a pivoted trigger for the firing pin and a momentum actuated body flexibly supported at its top and bottom, directly connected with said trigger adapted 90 to rotate said trigger about its axis to release the firing pin when the mine is engaged.

6. In a submarine mine, in combination, a casing having an air chamber, and explo- 95 sive-containing chamber, a firing mechanism chamber associated with the explosive chamber and containing a firing mechanism, said firing mechanism comprising a detonator, a firing pin adapted to coat therewith, a 100 spring adapted to be compressed by hydrostatic pressure when the mine is submerged, a firing lever engaging the firing pin, a trigger normally supporting said lever to hold 105 said firing pin in retracted position, and a 110

4
weight directly associated with said trigger adapted to be moved when the mine is engaged, to release said lever and explode the detonator by the expansion of said spring.

5 7. In a submarine mine, in combination, a casing having an air chamber at its upper part, an explosive-containing chamber in its lower part and a firing mechanism chamber associated with the explosive chamber and containing the firing mechanism, said firing mechanism comprising a detonator, a firing pin adapted to coact therewith, a spring adapted to be compressed when the mine is submerged, a firing lever engaging the firing pin, a pivoted trigger normally having sliding contact with said lever to support said firing pin in retracted position, a weight directly connected with said trigger adapted to be moved when the mine is engaged to withdraw the sliding contact of said trigger with said lever and explode the detonator by the expansion of said spring, and a safety device directly associated with one of said parts adapted to prevent actuation of said trigger until the mine is submerged.

8. In a submarine mine, in combination, a casing having an air chamber and an explosive-containing chamber, a firing mechanism chamber associated with the explosive chamber, said firing mechanism comprising a base, a tubular member, having a slot in one side, supported by said base and provided with means for forming a hydrostatic chamber between said base and said tubular member, communications between said hydrostatic chamber and the exterior of the mine whereby water may flow into said chamber when the mine is submerged, a firing pin within said tubular member, a spring adapted to tension said firing pin on the expansion of said hydrostatic chamber, a firing lever passing through said slot in said tubular member and engaging said firing pin, a pivoted trigger engaging said lever for normally maintaining said firing pin in retracted position, and momentum actuated means directly connected to said trigger for releasing the firing pin when a mine is engaged.

50 9. In a submarine mine, in combination, a casing having an explosive-containing chamber and a firing mechanism associated with the explosive chamber, said firing mechanism comprising a base, a tubular member supported by said base and provided with means for forming a hydrostatic chamber between said tubular member and base, said base plate having an opening adapted to permit water to enter said hydrostatic chamber, a removable closure for said opening, a firing pin carried by said tubular member, a spring adapted to be compressed as water enters said hydrostatic chamber, a pivoted trigger, a safety device directly associated with said tubular member and said

trigger adapted to prevent release thereof until the hydrostatic chamber has been filled, and a momentum actuated member directly associated with said trigger adapted to release the trigger after the mine has been submerged.

5 10. In a submarine mine, in combination, a casing having an air chamber, an explosive chamber and a firing mechanism chamber, one of said chambers having an opening therein, means closing said opening adapted to operate after a predetermined time thereby to allow water to enter said chamber and cause the mine to sink, said means comprising a tubular member provided with a side port, a movable valve operating within said tubular member for closing said port when in depressed position, soluble means exposed to the outside water and adapted to be dissolved when the mine is in use, for normally maintaining said valve in depressed position, means for elevating said valve when said soluble means is dissolved.

11. In a submarine mine, in combination, a casing having an air chamber, an explosive-containing chamber and a firing mechanism chamber, safety locked firing mechanism including a hydrostatic valve and a trigger member, a cam member adapted to be elevated by said valve, and coöperating with said trigger member to hold the same normally inoperative and adapted on elevation to unlock the firing mechanism.

12. In a submarine mine, in combination, a casing having an air chamber, an explosive containing chamber and a firing mechanism chamber, safety locked firing mechanism including a hydrostatic valve and a trigger member, movable means provided with a cam surface and actuated by said valve, said cam surface coöperating with said trigger member to maintain the same normally locked and adapted on actuation to unlock the firing mechanism.

13. In a submarine mine, in combination, a casing having an air chamber near one end and an explosive chamber near the other, one end of said chamber being concave and provided within such concavity with firing mechanism, said firing mechanism including a hydrostatically tensioned firing pin and a multi-arm trigger member, said trigger member comprising an arm coöperating with the firing pin to normally maintain it in depressed position, a second arm for coöperating with safety locking means, and a third arm for coöperating with trigger releasing means.

14. In a submarine mine, in combination, a casing having an air chamber, an explosive-containing chamber and a firing mechanism chamber, safety locked firing mechanism including a hydrostatic valve, a firing pin tensioned thereby, and a multi-arm trigger member, a cam plate adapted to be ele-

vated by said valve, said trigger member comprising an arm coöperating with the firing pin to normally hold it under tension, a second arm coöperating with said cam plate to provide safety locking means and released when said cam plate is elevated, whereby said weight may be oscillated to release said first named arm and permit the firing pin to be 25 operated.

15. In a submarine mine, in combination, a casing having an air chamber, an explosive-containing chamber and a firing mechanism chamber, safety locked firing mechanism including a hydrostatic valve and an integral multi-arm trigger member, a cam plate adapted to be elevated by said valve to release the safety lock, a balanced tripping weight, said trigger member comprising an arm coöperating with the firing pin to normally hold it cocked, a second arm to which said tripping weight is pivoted, and a third

arm coöperating with said cam plate to provide safety locking means and released when said cam plate is elevated, whereby said weight may be oscillated to release said first named arm and permit the firing pin to be 25 operated.

16. In a submarine mine, firing means therefor, comprising, a hydrostatically tensioned firing pin, a firing lever associated therewith, a pivoted trigger member coacting with said firing lever for normally holding said firing pin in depressed position, an oscillating weight directly connected to said trigger member at one end and flexibly supported at its other end, for releasing said 35 firing pin.

Signed at Washington, D. C., this 28th day of August, 1917.

CHESTER T. MINKLER.
